PUMPING MECHANISM

Chalon E. Bridwell, Detroit, Mich.

Application October 13, 1941, Serial No. 414,742

5 Claims. (Cl. 103—158)

My invention relates to a new and useful improvement in a pumping mechanism adapted for use on deep wells such as water, oil and gas wells. It is an object of the present invention to provide a pumping mechanism so constructed that the upper traveling valve and its seat may be protected against contact with sand or other abrasive or destructive material.

It is an object of the present invention to provide a construction whereby the liquid above the traveling valve is closed off and prevented from returning to the traveling valve or valve seat.

Another object of the invention is the provision of a construction in which the life of the traveling valve may be considerably increased, due to its protection from destructive and wearing elements.

Another object of the invention is the provision of an upper standing valve so constructed and arranged that it will be guided in its movements, free for rotation, and easily and quickly assembled in position.

Another object of the invention is the provision in a pump plunger having a plurality of sealing rings around its periphery for sealing the pump barrel.

Another object of the invention is the provision in a pump of this type of a pump plunger so constructed and arranged that a sand trap will be provided intermediate its ends.

Another object of the invention is the provision of a pump plunger operating in a pump barrel so constructed and arranged that a closer machined fit between the plunger and the barrel becomes unnecessary.

Another object of the invention is the provision of a construction so arranged that a pump barrel will carry a pull tube nut embracing the pull tube and in spaced relation thereto for providing necessary bleeding or leakage.

Other objects will appear hereinafter. It is recognized that various changes and modifications may be made in the detail of structure illustrated without departing from the invention herein set forth and it is intended that such modifications shall be brought within the scope of the claims forming a part hereof.

Forming a part of the specification is a drawing in which:

Fig. 1 is a fragmentary, longitudinal, sectional view of the invention.

Fig. 2 is a fragmentary, longitudinal, sectional view of the invention showing a continuance of the structure illustrated in Fig. 1.

Fig. 3 is a central, longitudinal, fragmentary, sectional view of the invention showing a continuance of the structure illustrated in Fig. 2.

Fig. 4 is a sectional view taken on line 4—4 of Fig. 1.

Fig. 5 is a sectional view taken on line 5—5 of Fig. 1.

Fig. 6 is a sectional view taken on line 6—6 of Fig. 2.

Fig. 7 is a sectional view taken on line 7—7 of Fig. 2.

Fig. 8 is a sectional view taken on line 8—8 of Fig. 2.

Fig. 9 is a sectional view taken on line 9—9 of Fig. 2.

In the drawing I have illustrated the invention as embodying a head valve structure comprising the tubular portion 17 which is cut away on its inner surface for a portion of its length to provide the space 18. This tubular portion is also provided with the inwardly projecting shoulder 19 which provides the valve seat surface 20. This tubular portion is also provided with the inwardly projecting shoulder 21 proceeding upwardly from

20 which is a reduced neck 22 having lateral openings 23 formed therein and terminating in the head 24. A threaded stem 25 is provided with the lock nut 26 and means for connecting the sucker rods thereto. A portion 27 of this rod

25 snugly engages as a slide fit in the bore formed in the head 24 and projecting downwardly from this portion 27 is the end 28 of reduced diameter which carries a valve head 29 and a valve head 30, these valve heads 29 and 30 being slidable

35 into and out of registration with the bosses or shoulders 21 and 19. When in engagement therewith, as shown in Fig. 1 the valve heads 29 and 30 serve as effective valves for closing the passage

40 through the member 17, the inner surface of the shoulders or bosses 19 and 21 serving as valve seats.

Carried by the stem 28 below the valve head 30 is a cup shaped valve embodying the bottom 32, the reduced base portion 31 and the portion 33.

45 Lateral openings 34 are formed in the cup shaped valve so as to establish communication between the interior thereof and the space 18. When moved into closing position as shown in Fig. 1, the outer face of the bottom 32 engages the face

20 and serves as a valve for closing the passage through the member 17. As the rod 25 is reciprocated relatively to the member 17 and moved downwardly from the position shown in Fig. 1, the valve head 32 will move out of engagement

with its seat while the valve heads 30 and 29 are still in closing position. As this downward movement of the rod 28 continues the valve heads 30 and 29 will move out of registration with the shoulders or bosses 19 and 21 so that the liquid would be permitted to pass from the space 18 upwardly into the interior of the neck 22 from which it may issue through the openings 23. As the rod 28 moves downwardly the nut 26, which may be adjusted on the threaded portion 25 to the proper position, will strike the end of the head 24 so that the member 17 will move downwardly in unison with the rod 28. On the reverse stroke the valve heads 29 and 30 will move into closing position before the valve head 32 engages its seat 20, thus the liquid above the valve head 32 is shut off from access to the valve head 32 before it moves into closing position. Experience has shown that in pumping oil, the sand has a tendency to settle and when settling on the valve 32 will have a tendency to wear away this valve and its seat. This, of course, results in pulling the pump and replacing the valve, an operation which is considerably expensive. The valves 29 and 30, serve as valves for protecting the upper traveling valve. When the valve head 32 finally engages on said seat 20, further upward movement of the stem 28 will, of course, move the member 17 and the stem 28 and its parts upwardly.

A nipple 35 is threaded onto the end of the member 17 and serves as a means for connecting to the member 17 the pump barrel 36 in which the plunger is slidably mounted. In the structure illustrated, I have indicated the pump barrel as being reciprocated with the plunger stationary. It is a well-known practice, however, that the plunger may be reciprocated and the pump barrel retained stationary, in which event the valve heads 29 and 30 would be used to protect the upper traveling valve which would move with the traveling plunger.

Slidably mounted in the pump barrel 36 is a tubular standing valve retaining head 37 having a bore 39 formed in its upper end 38, this upper end being enlarged to provide an engagement head against which engages the standing valve stop 47 which is annular in construction and provided with a pair of axially directed arms 46 carrying a head 45 through which projects a stem 44 projecting downwardly from the bottom or head 43 of a cup shaped valve embodying the lower reduced portion 41 and the upper portion 40 which slidably engages in a snug fit in the pump barrel. Openings 42 are formed in the reduced portion 41 so as to establish communication between the interior of the valve 40 and the interior of the pump barrel 36. After the stem 44 has been projected through the head 45, it is upset as at 49 so as to prevent its undue removal.

Connected to the lower end of the member 37 is the upper end of a plunger 50 which is provided, intermediate its ends, with ring grooves in which sealing rings 52, diagonally split as shown in Fig. 2, are mounted. By using these rings on the plunger 50, a fine machining of the plunger 50 so as to form a close fit with the inner surface of the pump barrel 36 becomes unnecessary and, thus a more economical construction is provided.

This comparatively loose fit between the plunger 50 and the pump barrel 36 permits the sand which may have lodged between the inner surface of the pump barrel 36 and the plunger to precipitate and enter the space 53 which is formed by reducing the diameter of the plunger

50. The plunger is provided, at its reduced portion, with openings 54 so that the sediment and liquid which may have precipitated into the space 53 may pass into the interior of the plunger which is formed tubular. The sediment and precipitant entering the sand trap or space 53 which enters the interior of the plunger through the openings 54 is thus again returned to the stream of liquid being pumped and agitated so that this abrasive, sedimentary material is thus held in and travels with the liquid. The removal of this material from between the plunger and the inner surface of the barrel results in less wear on the plunger and the barrel with consequent increase in life of the plunger and the barrel.

As shown in Fig. 3 the plunger 50 is also provided with a lower set of grooves 154 in which sealing rings 55 are provided. Projecting downwardly from the lower end of the plunger 50 is a threaded nipple 56 onto which is threaded the coupling 57 which connects to the upper end of the pull tube 58. This pull tube extends through a bore 61 formed in the pull tube nut 59 which is threaded onto the lower end of the pump barrel 36. It will be noted that there is a space 60 between the pump barrel 36 and the pull tube 58 and that liquid entering this space may be permitted to drain through the space 61.

What I claim as new is:

1. In a mechanism of the class described, adapted for use with a pump structure, a tubular member mounted on the upper end of the pump structure and projecting upwardly therefrom in alignment therewith and in communication therewith for providing a conduit for conducting liquid from said pump structure; a plurality of valve seats in said tubular member; a valve slidably mounted in said tubular member and movable relatively thereto and in unison therewith, 30 below and engageable with one of said valve seats, for controlling the flow of fluid through said tubular member and movable to open and closed positions; a stem connected to said valve and projecting upwardly therefrom outwardly of the upper end of said tubular member; and a valve structure carried by said stem above said valve for cooperating with one of the valve seats in said tubular member for controlling the flow of fluid through said tubular member and, upon movement of said stem in the direction for closing said first-named valve, engageable with its seat prior to the closing of said first-named valve, and upon movement of said stem in the opposite direction for opening said first-named valve disengageable from its seat subsequent to the opening of said valve.

2. In a mechanism of the class described, and adapted for use on a pump structure, a tubular member mounted on the upper end of said structure and projecting upwardly therefrom in alignment therewith and in communication therewith; a valve slidably mounted in said tubular member and movable relatively thereto and in unison therewith for controlling the flow of fluid therethrough and movable to open and closed positions; a stem connected to said valve and projecting outwardly beyond the upper end of said tubular member and slidably therein for moving said valve to open and closed position; and a plurality of spaced apart means cooperating with said stem and said tubular member for guiding said stem and said valve in its slidable movements relatively to said tubular member.

3. In a mechanism of the class described, adapted for use with a pump structure including

a reciprocating barrel and stationary plunger, a tubular member mounted on the upper end of said barrel and projecting upwardly therefrom, in alignment therewith and in communication therewith for providing a conduit for conducting fluid upwardly through said barrel; a valve slidably mounted in said tubular member and movable relatively to said barrel and in unison therewith and movable to open and closed position for controlling the flow of fluid through said tubular member; a plurality of valve seats formed on the inside of said tubular member above said valve; a plurality of valve heads engageable with said plurality of valve seats; and means connected to said valve and said valve heads and projecting beyond the upper end of said tubular member for moving said valve and valve heads relatively to their seats, said valve heads upon movement to closed position, being movable into engagement with their seats prior to the engagement of said valve with its seat.

4. In a mechanism of the class described adapted for use on a pump structure embodying a reciprocating tubular member, a tubular fitting secured to the upper end of said tubular member and projecting upwardly therefrom and in alignment therewith and in communication therewith; a valve seat-forming member in said fitting and projecting inwardly from the inner surface thereof; a valve slidably mounted in said fitting and positioned below said seat and movable upwardly into engagement with said seat for controlling the flow of fluid through said fitting; a plurality of slide valve seats in said fitting in spaced relation to each other and positioned above said first-named valve seat; a stem connected to said valve and projecting outwardly beyond the upper end of said fitting and slidable therein for moving said valve to opened and closed positions; and a plurality of valve heads on said stem in spaced relation to each other for simultaneously engag-

ing said slide valve seats for controlling the flow of fluid through said fitting, the bearing surfaces of said valve heads and said slide valve seats being sufficiently large for retaining said valve heads in engagement with said slide valve seats subsequent to the opening of said first-named valve and prior to the closing of said first-named valve.

5. In a mechanism of the class described adapted for use on a pump structure embodying a reciprocating tubular member, a tubular fitting secured to the upper end of said tubular member and projecting upwardly therefrom and in alignment therewith and in communication therewith; a valve seat-forming member in said fitting and projecting inwardly from the inner surface thereof; a valve slidably mounted in said fitting and positioned below said seat and movable upwardly into engagement with said seat for controlling the flow of fluid through said fitting; a plurality of slide valve seats in said fitting in spaced relation to each other and positioned above said first-named valve seat; a stem connected to said valve and projecting outwardly beyond the upper end of said fitting and slidable therein for moving said valve to opened and closed positions; and a plurality of valve heads on said stem in spaced relation to each other for simultaneously engaging said slide valve seats for controlling the flow of fluid through said fitting, the bearing surfaces of said valve heads and said slide valve seats being sufficiently large for retaining said valve heads in engagement with said slide valve seats subsequent to the opening of said first-named valve and prior to the closing of said first-named valve, the diameter of said fitting being sufficiently small at a portion of its length for engaging said first-named valve and serving as a guide therefor and the diameter of said fitting above said valve heads being sufficiently small for engaging said stem as a guide.

CHALON E. BRIDWELL.
